UNITED STATES PATENT OFFICE

LOUIS H. VERONNEAU, OF MONTREAL, QUEBEC, CANADA

ELECTRIC BOILER

Application filed October 27, 1928. Serial No. 315,446.

This invention relates to new and useful improvements in water heaters and particularly to electrically operated heaters for heating water for domestic purposes.

5 According to my invention I provide a boiler having an interior chamber in which steam is generated by an electrical heating element. The heat from the steam is absorbed by water circulation from the boiler 10 through a plurality of small tubes passing through the said chamber. Means are provided for keeping the water in the chamber at a predetermined level.

In the drawings which illustrate the preferred form of my invention:

Figure 1 is a part sectional side elevation of my improved heater.

Figure 2 is a sectional plan taken on the line 2—2 Figure 1.

20 Referring more particularly to the drawings, 11 designates a cylindrical boiler having an outlet 13, and an inlet 12 connected to a source of water supply. A safety valve 14 may be mounted on the top of the boiler. 25 Mounted on a central casting 15 is a tube 16 which extends upwardly and is spaced from the top of the boiler. The top of the tube is provided with a cap 17 having a series of perforations 18 to receive the ends of a plurality of comparatively small pipes 19. The lower ends of these pipes are curved outwardly and fit into apertures 20 formed in the lower end of the tube 16. The ends of the pipes are expanded to form watertight joints 30 between their outer walls and the tube which forms a steam chamber. Secured to the casting and to the boiler in proximity to the end of the tube is the water chamber bottom 21. 35 The casting 15 is secured to the bottom 22 of the boiler and said bottom is centrally apertured and recessed to receive the flange 23 which supports the heating elements 24. The heating elements may be of any of the well known electrical types. Each element in the 40 heater shown comprises an inner tube 25 and an outer tube 26. The inner tube is insulated from the flange 23 and is supported on studs or bolts 27 passing through the flange but insulated therefrom. The studs are connected in series and to a source of electrical cur-

rent supply. The outer tubes are perforated and are secured to the flange to which the return wire for the circuit is attached. Any number of elements may be used and a guard 28 may be secured to the flange to protect the 55 wire connections. Extending outwardly from the side of the boiler near the bottom thereof is the bracket 29 which supports a reservoir 30 the lower end of which has a downwardly extending tube 31 which fits into a cup 32 communicating with the steam generating chamber 33 by means of the tube 34. The lower end of the tube 31 is so positioned that the water in the steam generating chamber is kept at a predetermined level. When 60 the water in the cup falls below the end of the tube 31 water from the reservoir flows into the cup until the end of the pipe is sealed by the water in the cup. A centrally disposed pipe 35 extends upwardly from the cup 65 through the top of the boiler and is covered by a safety valve shown diagrammatically at 36.

70 In operation current is supplied to the heating elements, the circuit passing through the layers of water between the tubes of each element. The resistance of the water to the passage of the current develops heat and the water in the steam generating chamber develops into steam. The steam rises into the tubes and comes in contact with the walls of 75 the small water circulating pipes. The water in the boiler is heated rapidly by the transfer of heat from the steam to the pipes and circulates in the manner shown by the arrows 87. Any of the well known types of thermostats 80 may be connected to the current supply to hold the heat of the boiler between predetermined temperatures. A thermostat is shown diagrammatically at 38. The device is 85 very simple in construction and provides an efficient means for heating water for domestic purposes. Safety valves are provided for the steam generating chamber and the boiler water chamber. The reservoir for the steam 90 generating chamber is removably secured to the bracket on the side of the boiler to facilitate supplying water to the said chamber.

95 It will be readily understood that many modifications may be made in the construc- 100

tion features of the device without departing from the spirit of the invention.

Having thus described my invention, what I claim is:—

- 5 1. In an electric boiler, an outer casing, a steam chamber within the outer casing, an electric heating element within the steam chamber and water circulating pipes extending upwardly through the steam chamber,
- 10 10 said pipes communicating at both their ends with the space between the steam chamber and the outer casing.
- 15 2. In an electric boiler, an outer casing, a tube within the outer casing, a perforated cap for the top of said tube, said tube communicating with a steam generating chamber at its lower end, an electric heating element in the generating chamber and water circulating tubes extending upwardly within the steam
- 20 26 chamber, said tubes at their upper ends being expanded in the cap and at their lower ends passing through the tube and expanded therein.

In witness whereof, I have hereunto set
25 my hand.

LOUIS H. VERONNEAU.
